FLEXIBLE CEMENT ROOFING

Harold W. Greider, Wyoming, and George A. Fasold, Cincinnati, Ohio, assignors to The Philip Carey Manufacturing Company, a corporation of Ohio

Application September 6, 1935, Serial No. 39,446

20 Claims. (Cl. 108—7)

This invention relates to prepared roofing and is particularly addressed to providing a lap for prepared roofing to extend over the nail heads in, and to be fixedly secured to, the top of the next adjacent ply or layer of roofing applied on a structure. While the invention has been shown as particularly adapted to roofing, of course, it may also be used for siding and other like surfacing where a protective material is desired such

10 as flexible prepared roofing.

In the drawings:

Fig. 1 is a vertical sectional view showing the roofing applied;

Fig. 2 is a transverse sectional view of a portion 15 of prepared roofing showing one longitudinal edge and the flap;

Fig. 3 is a diagrammatical showing of the various parts of Fig. 1;

Figs. 4, 5 and 6 are fragmentary perspective 20 views showing various steps in the fabrication of another modification; and

Fig. 7 is a fragmentary perspective view of two roofing sheets embodying the invention in overlapping relation.

25 In the drawings, in which like characters relate to like parts A is a foundation upon which the flexible roofing material is built. This foundation is preferably a sheet of asphalt saturated felt, although asphalt impregnated burlap or other suitable fabric may be used. To each surface of this foundation A may be applied a layer 30 of coating asphalt of desired character. The saturated felt sheet forming the foundation is scored at K so as to provide an end portion C¹ which may be readily detached from the body C of the foundation A. As stated above layers of asphalt are preferably applied to the upper and lower surface of the foundation. The lower layer, however, may, if desired, be dispensed with

35 but the top layer D is the cementing layer or mastic into which is embedded a woven fabric strip F, preferably a canvas or burlap that has been saturated with asphalt. This canvas extends the entire length of the roofing sheet but 40 extends only a portion of the way across the sheet.

45 As clearly shown in Fig. 3 the saturated canvas is arranged so that it has one edge registering with the edge of the foundation portion C¹ and extends inward over the scoring K to a point intermediate the scoring and the opposite edge 50 of the foundation A, the distance depending upon the amount of lap that it is desired to have. To the surface of this is applied a layer H of sand or other suitable fine granular or powdered material placed therein to prevent adhesion of a

superposed layer of the prepared roofing to the saturated canvas strip F. Over the strip F is a layer E of asphalt saturated burlap which is co-extensive in area with the area of the saturated felt foundation A.

5 In the manufacture of the roofing, it is preferable to stitch, by a row of stitching G extending longitudinally of the saturated burlap and the saturated canvas strip before applying the saturated canvas and the burlap to the layer of asphalt D on top of the saturated felt foundation A. The saturated burlap is held in adhesive contact with the saturated felt foundation A by the layer of asphalt D on top of the foundation A except that area of the burlap sheet E which extends 10 over the saturated canvas F. This area is kept free from adhesion or permanent adhesion with the saturated canvas F by a layer of sand applied over the surface of the canvas F as described above. After the burlap has been cemented to the foundation as stated, it may be given a coating of asphalt and sand or other suitable fine mineral may be applied over the weather surface either in the form of powder, granules or flakes and the lower surface of the saturated felt 15 foundation A is preferably coated with soapstone or other suitable non-adhering material to prevent adhesion of the convolutions, after which the prepared roofing is rolled for transportation.

20 In the application of the improved roofing a 25 ply of the roofing B is laid on the roof and nailed in position thereon by nails or otherwise held in contact with the roof as for instance at J in Fig. 1. The next layer of roofing, as shown in Fig. 1, is then ready for application. Before applying it, 30 however, the portion C¹ is removed along the scoring K, which removes a portion of the saturated felt shown as C¹ in Fig. 2 and a portion of the saturated canvas F with the sand coating H. The canvas F is provided with a scoring as is the 35 felt foundation A as indicated in Figure 3. Then the ply of roofing is laid so that what was formerly the scoring K has, by removal of the portion C¹, become the longitudinal edge of the roofing proper and this is laid close against the layer of 40 roofing B as shown in Fig. 1, after which the flap shown in Fig. 2 consisting of the loose portion of the saturated burlap strip E is, after the roofing has been nailed or otherwise fixed in place, brought down over the nail J as shown in Fig. 1, 45 if nails are used, and then cemented by a suitable cement, such as asphalt, to the top surface of the sand in the roofing strip to which the flap is attached and to the top surface of the next adjacent strip B, as shown in Fig. 1, so as to fixedly 50

55

secure the flap in place. It will be seen that this prepared roofing applied as stated seals and protects nail heads and any joints between adjacent plies of roofing so as to avoid any deterioration 5 of the roofing as it is applied by reason of any openings in the joints or any corrosion of the nails and has many other advantages. It will be noted that by having the portion C' left in place but readily detachable, the roofing can be rolled 10 without danger to the flap edge that would arise if the flap were not provided with the underlying protecting portion C', especially when the roofing was being rolled and handled in transportation, since the flap end of the roll would not have 15 sufficient strength to support the weight of the roll proper.

Another modified form of the invention is disclosed in Figures 4 to 7 inclusive. In this modification a burlap sheet E' has one edge folded at 20 M to provide a retroverted portion N which may be stitched to the main body of the sheet at G'. This sheet may be so folded previous to or after it has been treated with a saturant. In order to provide free overlapping edges, there may be interposed between the main body of the sheet E' and the retroverted end N any suitable non-adhesive material L, typified herein by a thin sheet 25 of paper or similar material. This paper sheet may be adhered or otherwise secured with one face in contact with the bottom side of the burlap sheet E'. The exposed or undersurface of the paper sheet is non-adhesive. Accordingly when the end of the burlap sheet is retroverted and stitched with the base portion of the sheet 30 at G' the contacting surfaces of the paper sheet will be non-adhesive. Thereafter the edge portion O may be cut away as indicated on the line P in order to render the non-adhesive edges free 35 for overlapping. The retroverted portion N may be perforated or otherwise weakened at K' directly over the weakened portion K in the saturated felt sheet A to partially sever a marginal strip Q therefrom. During shipment the strip Q may be left in place to serve as a packing or 40 filling strip to protect the overlapping edge and when the roofing is ready to be applied on the job the applicator may remove the packing or filling strip Q, said strip being readily removable by reason of its weakened adherence to the roofing 45 sheet.

Two similarly constructed roofing sheets are preferably overlapped as illustrated in Figure 7 with a plain edge R on one sheet overlapped by the lapping edge constructed as above described. 50 The overlapped edges are secured by any suitable nailing means S, and then a filling material T of bituminous cement or the like is applied over the nails and the joint seam beneath the lap U which is thereafter secured in place by the cement. In this construction it will be readily apparent that in the overlapping edge the nails are entirely concealed and protected by the lap and the lapping edge securely covers the nails 55 and seals the seam between the adjacent edges of the roofing sheet. It will also be noted that the weather exposed surface of each roofing sheet consists of a smooth, continuous sheet of asphalt impregnated, coated and mineral surfaced fabric, 60 without fold or seam at the lap.

While we have illustrated and described different embodiments of the invention it will be understood that there may be various changes in details of construction without departing from 65 the spirit of same.

We claim:

1. In a flexible sheet roofing, a bituminous saturated layer, a bituminous impregnated layer in adhesive contact therewith over the greater portion thereof, said last mentioned layer being 5 free of engagement with said first layer along one edge thereof, said first layer having a portion adapted to be easily removed from said layer along a line longitudinally of and intermediate the longitudinal edges of the portion that is free 10 of engagement with the layer above it.

2. In a flexible sheet roofing, a bituminous saturated layer, a bituminous impregnated layer in adhesive contact therewith over the greater portion thereof, said last mentioned layer being 15 free of engagement with said first layer along one edge thereof, said first layer having a scoring so as to provide a portion adapted to be easily removed from said layer along a line longitudinally of and intermediate the longitudinal edges of the portion that is free of engagement with the layer above it.

3. In a flexible roofing, a bituminous saturated layer having a readily removable marginal strip, and a bituminous impregnated layer in adhesive 25 contact therewith over the greater portion thereof, said last mentioned layer being free of engagement with the readily removable strip and projecting over the readily removable strip and provided with a non-adhesive face portion. 30

4. In a flexible sheet roofing, a layer of bituminous saturated felt, a layer of impregnated fabric overlaying and in adhesive engagement with, except along a portion adjacent the edge of, said saturated felt and projecting beyond one 35 edge thereof to provide an offset, a sub-layer of impregnated woven fabric in adhesive engagement with said felt and coextensive with and overlaying said portion of the felt with which the second layer is not in engagement, and means provided whereby a portion of said second layer above said woven fabric sub-layer is free of said woven fabric-sub-layer.

5. In a flexible sheet roofing, a layer of bituminous saturated felt, a layer of impregnated open mesh woven fabric over-laying and in adhesive engagement with, except along a portion adjacent the edge of, said saturated felt and projecting beyond one edge thereof to provide an offset, a sub-layer of impregnated woven fabric 50 in adhesive engagement with said felt and coextensive with and overlaying said portion of the felt with which the second layer is not in engagement, and means provided whereby a portion of said second layer above said woven fabric sub-layer is free of said woven fabric-sub-layer.

6. In a flexible sheet roofing, a layer of bituminous saturated felt, a layer of impregnated open mesh woven fabric overlaying and in adhesive engagement with, except along a portion 60 adjacent the edge of, said saturated felt and projecting beyond one edge thereof to provide an offset, a sub-layer of impregnated woven fabric in adhesive engagement with said felt and coextensive with and overlaying said portion of the felt with which the second layer is not in engagement, a non-adhesive material arranged between the said second layer and a portion of said woven fabric to prevent adhesion of same.

7. In a flexible sheet roofing, a layer of bituminous saturated felt, a layer of impregnated material overlaying and in adhesive engagement with, except along a portion adjacent the edge of, said saturated felt, a sub-layer of impregnated fabric in adhesive engagement with said felt and 75

coextensive with and overlaying said portion of the felt with which the second layer is not in engagement, and means provided whereby a portion of said second layer above said fabric sub-layer is free of said fabric sub-layer, and means whereby a portion of the saturated felt and fabric sub-layer may be readily removed.

8. In a flexible sheet roofing, a layer of bituminous saturated felt, a layer of impregnated open mesh woven fabric overlaying and in adhesive engagement with, except along a portion adjacent the edge of, said saturated felt, a sub-layer of impregnated woven fabric in adhesive engagement with said felt and coextensive with and overlaying said portion of the felt with which the second layer is not in engagement, and means provided whereby a portion of said second layer above said woven fabric sub-layer is free of said woven sub-layer, and means intermediate the longitudinal edges of said woven sub-layer fixedly attaching said sub-layer to the second layer.

9. In a roof, a roof covering composed of a plurality of sheets of flexible roofing material, each of said sheets having a foundation layer arranged in the same plane with a foundation layer of the next adjacent sheet, a layer of woven material arranged over and in adhesive contact with said foundation layer adjacent one edge thereof, a layer of mesh material overlaying and in adhesive engagement with said foundation layer and extending beyond an edge thereof to overlap a portion of an adjacent sheet, said mesh material being fixedly attached to said woven material intermediate the edges of said woven material, and in adhesive engagement with said woven material and the portion of next adjacent sheet of roofing which it overlaps.

10. In a roof, a roof covering composed of a plurality of sheets of flexible roofing material, each of said sheets having a foundation layer arranged in the same plane with a foundation layer of the next adjacent sheet, a layer of woven material arranged over and in adhesive contact with said foundation layer adjacent one edge thereof, a layer of mesh material overlaying and in adhesive engagement with said foundation layer and extending beyond an edge thereof to overlap a portion of an adjacent sheet, said mesh material being fixedly attached to said woven material intermediate the edges of said woven material, and in adhesive engagement with said woven material and the portion of next adjacent sheet of roofing which it overlaps, and means passing through said woven material and said foundation layer fixedly attaching same to the roof.

11. In a roof, a roof covering composed of a plurality of sheets of flexible roofing material, each of said sheets having a foundation layer arranged in the same plane with a foundation layer of the next adjacent sheet, a layer of woven material arranged over and in adhesive contact with said foundation layer adjacent one edge thereof, a layer of mesh material, having a mineral top surface, overlaying and in adhesive engagement with said foundation layer and extending beyond said foundation layer over a portion of an adjacent sheet, said mesh material being fixedly attached to said woven material intermediate the edges of said woven material, and in adhesive engagement with said woven material and the portion of the next adjacent sheet of roofing which it overlaps.

12. A prepared flexible sheet roofing having a foundation layer of bituminous saturated felt, a

relatively narrow layer of woven fabric overlaying and in adhesive contact with said felt, a layer of bituminous material overlaying said felt and under said woven fabric, a layer of bituminous impregnated burlap projecting beyond one end of said felt and overlaying said felt and said woven material and in adhesive engagement with said felt by means of said layer of bituminous material and fixedly attached to said woven fabric, means to prevent a portion of said woven fabric from adhesive engagement with said burlap, a bituminous coating on said burlap and a surfacing thereover of mineral particles.

13. A prepared flexible sheet roofing having a foundation layer of bituminous saturated felt, a relatively narrow layer of woven fabric overlaying and in adhesive contact with said felt, a layer of bituminous material overlaying said felt and under said woven fabric, a layer of bituminous impregnated fabric coextensive with said felt and overlaying said felt and said woven fabric material and in adhesive engagement with said felt by means of said layer of bituminous material and fixedly attached to said woven fabric, means to prevent a portion of said woven fabric from adhesive engagement with said impregnated fabric, a bituminous coating on said impregnated fabric and a surfacing thereover of mineral particles, said felt and narrow layer of woven fabric being scored longitudinally so as to provide means for readily detaching a portion of the felt and woven fabric whereby the impregnated fabric layer will extend beyond the edge of the felt and provide a lap to extend over the next adjacent roofing sheet when applied.

14. In a flexible sheet roofing, a bituminous saturated layer, a bituminous impregnated layer adhesively secured thereto over the greater portion thereof and retroverted at one edge, means inserted between the layers of the retroverted portion to render them non-adhesive and free from engagement, and a portion of the impregnated layer projecting beyond the edge of the saturated layer.

15. In a flexible roofing, a bituminous saturated layer, a bituminous impregnated layer adhesively secured thereto over the greater portion thereof and including double layers at one edge, means inserted to keep the double layers free from engagement along the edge, and a portion of one of the double layers adapted to be readily removed to cause the other layer to provide a stepped lapped portion.

16. In a flexible roofing, a bituminous impregnated layer, a second bituminous impregnated layer adhesively secured thereto over the greater portion thereof and including double layers at one edge, and means inserted to keep the double layers free from engagement with each other along the edge and means provided whereby a portion of one of the double layers may be readily removed.

17. A prepared flexible sheet roofing having a foundation layer of bituminous saturated felt, a relatively narrow layer of impregnated woven fabric overlaying and in adhesive contact with said felt, a layer of bituminous material overlaying said felt and under said woven fabric, a layer of bituminous impregnated fabric coextensive with said felt and overlaying said felt and said woven fabric and in adhesive engagement with said felt by means of said layer of bituminous material and fixedly attached to said woven fabric, means to prevent a portion of said woven fabric from adhesive engagement with said

bituminous impregnated fabric, a bituminous coating on said bituminous impregnated fabric and a surfacing thereover of mineral particles, said felt being scored longitudinally so as to provide means for readily detaching a portion of the felt whereby the bituminous impregnated fabric layer will extend beyond the edge of the felt and provide a lap to extend over the next adjacent roofing sheet when applied.

10 18. The method of making a weather surfacing sheet comprising impregnating a fabric foundation with waterproofing material, providing an edge with lap portion having a face juxtaposed in non-adhesive contact with a face portion of the foundation, and scoring the foundation to remove a portion of the foundation which is contiguous to the lap portion.

15 19. A roofing sheet comprising a fabric foundation impregnated with waterproofing material,

a lap portion provided on one edge having one face juxtaposed in non-adhesive contact with a face portion of the foundation, and scoring provided in a portion of the foundation which is contiguous to the lap portion to provide a readily 5 removable portion of said foundation.

20. The method of making a weather surfacing sheet comprising impregnating a fabric foundation with waterproofing material, superposing along the longitudinal margin of the 10 foundation a waterproofed fibrous sheet, applying non-adhesive material to the underface of a portion of the superposed sheet, and removing from the foundation a marginal strip lying beneath the superposed sheet to provide a lap por- 15 tion.
